UNITED STATES PATENT OFFICE.

MARCIUS C. RICHARDS, OF AURORA, ILLINOIS, ASSIGNOR TO HIMSELF AND THE WILCOX MANUFACTURING COMPANY, OF SAME PLACE.

RAIL-SUPPORT FOR DOOR-HANGERS.

SPECIFICATION forming part of Letters Patent No. 394,611, dated December 18, 1888.

Application filed May 16, 1888. Serial No. 274,056. (No model.)

To all whom it may concern:

Be it known that I, MARCIUS C. RICHARDS, residing at Aurora, in the county of Kane and State of Illinois, and a citizen of the United States, have invented a new and useful Improvement in Rail-Supports for Door-Hangers, of which the following is a specification, reference being had to the accompanying drawings, in which—

10 Figure 1 is an end elevation, some parts being in section. Fig. 2 is a perspective showing one end of a rail secured in position; and Fig. 3 is a front elevation of two supporting-brackets, with portions of two sections of the track.

This invention relates to an improvement in supporting-brackets for holding the track-rails upon which the wheels or rollers of a door-hanger run, and has for its object to 20 provide a support for such rails, preferably made of one piece of metal, which can be readily attached to the building where it is designed to be used, and which will furnish a firm support for the rail and prevent undue 25 motion thereof when the door is being opened or closed and any liability to sag at the joints; and its nature consists in the novel bending of the material from which the support is made, so that a flat face is formed to rest 30 against the wall of the building to which it is attached, and a bracing portion is formed having at its lower end a socket in which the rail is placed, all as hereinafter more specifically described. That which I claim as new 35 will be pointed out in the claim.

In the drawings, A represents the supporting-bracket, formed, as shown, of a single strip of metal.

The strip from which the bracket is formed 40 is bent to form a horizontal bottom piece, a, having a turned-up end, b, and a vertical back piece, c. At the point indicated by d the strip is bent on itself to form another vertical portion, e, which rests against the face of

the portion c. At a point about one-half way down the piece c the strip is again bent to 45 form an inclined piece, f, which incline continues to a point just above and past the turned-up end b, and then the strip is bent to form a vertical piece, g, a short horizontal piece, h, and another vertical piece, i, the parts g, h, and i forming a socket, B, which receives a rail of the track.

The bracket A is attached to the wall of a building or other support by suitable screws 55 passing through holes formed in the vertical portions c e.

C are track-rails of ordinary construction, which rest in the socket B, and are secured in position by bolts which pass through them 60 and through the vertical portions g i and the turned-up end b, thus holding the rail firmly in place and strengthening the bracket by drawing the turned-up end b close against the inner wall, g, of the socket.

D is a hanger provided with a wheel, as usual.

E is a section of the wall or other support to which the supporting-bracket A is attached.

If desired, the support could be formed in 70 two pieces, one of which would form the parts a b c. The parts a b c form a brace. The upturned part b, the two parts g i of the socket, and the rail are all firmly held together by a single rivet.

What I claim as new, and desire to secure by Letters Patent, is as follows:

The support A, formed substantially as shown, and having a socket, B, to receive the rail, and a turned-up end, b, lying against one 80 wall of the socket, whereby one bolt will pass through such end b and through both walls of the socket and the rail, substantially as and for the purpose specified.

MARCIUS C. RICHARDS.
